Primary Examiner — Angela J Lee(74) *Attorney, Agent, or Firm* — Sand & Sebolt(57) **CLAIM**

The ornamental design for a nightlight, as shown and described.

DESCRIPTION

FIG. 1 is a front right top isometric perspective view of a new ornamental design for a nightlight;
 FIG. 2 is a front elevation view of the nightlight of FIG. 1;
 FIG. 3 is a rear elevation view of the nightlight of FIG. 1;
 FIG. 4 is a right side elevation view of the nightlight of FIG. 1, the left side elevation view being a mirror image thereof;
 FIG. 5 is a front right top isometric perspective view of a second embodiment of the new ornamental design for a nightlight;

FIG. 6 is a front elevation view of the nightlight of FIG. 5;
 FIG. 7 is a rear elevation view of the nightlight of FIG. 5;
 and,

FIG. 8 is a right side elevation view of the nightlight of FIG. 5, the left side elevation view being a mirror image thereof.
 The broken lines shown in the drawings represent portions of the nightlight that form no part of the claimed design.

1 Claim, 8 Drawing Sheets(56)
